CARL E. CHRISTOPHEL, OF PEARL RIVER, NEW YORK, ASSIGNOR TO DEXTER FOLDER COMPANY, OF PEARL RIVER, NEW YORK, A CORPORATION OF NEW YORK.

SHEET-FEEDING MACHINE.

1,410,996.

Specification of Letters Patent. Patented Mar. 28, 1922.

Application filed October 29, 1919. Serial No. 334,264.

To all whom it may concern:

Be it known that I, CARL E. CHRISTOPHEL, a citizen of Germany, residing at Pearl River, county of Rockland, and State of New York, have invented certain new and useful Improvements in Sheet-Feeding Machines, of which the following is a specification.

This invention relates to sheet feeding machines and has for its primary object to provide an improved construction and arrangement of parts in sheet feeding machines whereby combing wheels arranged in tandem and cooperatively driven are rendered effective on sheets of smaller size than have heretofore been effectively operated upon by machines of this character. One of the objects of the present invention is to provide improved means whereby the sheet feeding pressure exerted by a combing wheel upon a pile of sheets, may be cushioned in such a way as to produce a more effective separation between the sheets and equalization of pressure between combing wheels arranged in tandem. Another object of invention is to provide pack advancing means of improved construction according to which in the present embodiment of my invention, the thickness of the pack operated upon by the combing wheel or wheels is automatically controlled by the duration of the combing period. For this purpose, suitable mechanism is provided which is set for operation during a prolonged combing period but which only becomes fully operative for imparting the pack feed movement during those periods in which the periodic cam holds the comb or combers away from the pile or pack. Other and further objects will appear in the specification and be pointed out in the claims, reference being had to the accompanying drawings in which,

Figure 1 is a top plan view of a sheet feeding machine embodying the principles of this invention;

Figure 2 is a side elevation of the same taken from the left of Figure 1;

Figure 3 is a section on the line 3—3 Figure 1;

Figure 4 is a section on the line 4—4 Figure 1;

Figure 5 is a section on the line 5—5 Figure 1;

Figures 6 and 7 are outline elevations of the parts shown in Figure 4 for illustrating

different stages of the sheet feeding operation.

Figure 8 is a fragmentary section.

As shown in Figure 1, a power shaft 1 journaled in a bracket 2 mounted on the main frame 3 of the sheet feeding machine, carries a bevel pinion 4 which meshes into a similar pinion (not shown) which is keyed to the lower end of a shaft 5. Keyed to the upper end of said shaft 5 is a bevel gear 6 which meshes with a bevel gear 7 on the right end of a main drive cam shaft 8, said cam shaft being journaled in oppositely disposed side frames 9 and 10 which are mounted on the main frame 3. On the left end of the cam shaft 8 is mounted a large cam 11 which as shown in Figure 2, is adapted to operate on a cam roller 12 journaled on the upper end of a ratchet lever 13, said ratchet lever being freely journaled on a pack feed shaft 14. Pivottally mounted at 15 on a rearwardly presented arm of the ratchet lever 13 is a pawl 16 which engages a ratchet 17 on the pack feed shaft 14. According to the present embodiment of my invention, a plurality of laterally spaced feed tape rollers 18 are keyed to the shaft 14. Over these feed rollers pass the forward ends of endless feed tapes 19. The upper runs of these feed tapes travel above the pack carrying table 20 and when said feed tapes are moved, the pile P is thickened beneath the combing feed rollers to be hereinafter referred to. Projecting rearwardly from the ratchet lever 13 is an arm 21 provided with a hook 22, said hook being adapted to cooperate with a hook 23 on the forward end of a latch lever arm 24 which is keyed to a rock shaft 25. It will be understood that whenever the hooks 22 and 23 are in engagement with each other, the ratchet lever 13 is prevented from following into the inner run of the cam 11 under the pull of a spring 26 which is connected at one end to a fixed pin 27 and at its other end to a pin 28 carried by the ratchet lever 13. An adjustable stop pin 29 may be suitably mounted in the side frame 10 to limit the throw of ratchet lever 13 to impart a movement to ratchet 17 of one, two, or more teeth as desired or as may be called for by the character of the paper which is being handled in the machine. As shown in Figure 1, the rock shaft 25 is journaled in a rearwardly presented boss on the side frame 10. The inner end of the rock shaft 25 carries a

collar 30 (see Figure 3) to which is secured a spring arm 31 which is adapted under certain conditions to fulfill the functions of a cam arm. The spring 32 which is secured at 5 one end to a fixed pin 33 and at its other end to the spring arm 31, tends to hold the hooks 22 and 23 in engagement with each other.

Whenever the sheet combing device, to be presently described, drops to the pack of 10 sheets on feed table 20, the spring arm 31 is depressed in a way which tends to separate the hooks 22 and 23 and thus, tends to permit a pack feed operation. Keyed to the cam shaft 8 between the side frame 10 and 15 the cam 11 is a large spur gear 34 (see Figure 1) which, as shown in Figure 2, meshes with the smaller gear 35 of a compound gear which is journaled on a pin 36 on the side frame 10. The larger gear 37 of said compound gear, meshes with a gear 38 which is keyed to a combing wheel drive shaft 39, said combing wheel drive shaft being journaled in the side frames 9 and 10 as shown in Figure 1. Referring now to Figure 3, the drive 20 shaft 39 has keyed thereto a spur gear 40 which is connected by idlers 41 to a spur gear 42 which is keyed to a combing wheel shaft 43. The left end of shaft 43 as well as the pins 44 upon which the idlers 41 are 25 journaled, are carried by a lever arm 45 in the form of a gear housing. The right end of the combing wheel shaft 43 is journaled in a lever arm 46. As shown in Figure 4, the drive shaft 39 extends through a sleeve 47 to 30 which are keyed the lever arm housing 45 and the lever arm 46. According to the present embodiment of my invention, about midway between the lever arms 45 and 46 is disposed a gear housing 48 within which the 35 combing wheel shaft 43 is journaled. Said gear housing 48 is therefore rotatably supported on the shaft 43. In order to hold it in definite angular relation to the shaft 43, said gear housing is provided with a forwardly and upwardly presented extension 48' which as shown best in Figures 6 and 7 is provided with bifurcated arms 49 and 50 which carry adjustable screws 51 which bear 40 on the sleeve 47 for determining the angular position of said gear housing. As shown in 45 Figure 1, a combing wheel 52 is keyed to the shaft 43. Adjacent thereto, a gear 53 is keyed to the shaft 43, said gear 53 being in mesh with an idler 54 which transmits power 50 to a gear 55 for driving a second combing wheel 56 journaled on a shaft 57 in the rear end of gear housing 48. Referring more especially to Figure 1, the sleeve 47 is adapted to be oscillated on the drive shaft 39 by 55 means of a cam arm 58 which is preferably made integral with the boss 59 from which projects the lever arm housing 45. On one side of the cam arm 58 is journaled a cam roller 60 which runs on a periodic cam 61 60 which is secured by a set screw 62 of the

cam shaft 8. On the other side of the cam arm 58 is journaled a cam roller 63 which runs on a cam 75 which turns freely upon the cam shaft 8 but is provided with a laterally projecting pin 65 to which is connected 70 one end of a spring 66, the other end of said spring being connected to a pin 67 carried by an arm 68 which is keyed to a stay shaft 69 which extends between the side frames 9 and 10. In order to provide suitable and efficient means for equalizing the actions of the combing wheels 52 and 56, the pack feeding board or table 20 is provided with an arcuate recess or hollow 70 beneath the combing wheel 52, said hollow being covered 75 by a spring plate 71 over which the sheets are fed by the pack feed mechanism. Where, as in the present embodiment of my invention, the pack feed belts 19 have their upper runs arranged above the table 20, it is 80 desirable to have the feed table 20 provided with a spring plate 71 as shown in Figure 8 and to cover said spring plate with a strip of leather or other suitable material 72, the upper surfaces of the feed belts 19 and the 85 leather strip 72 being arranged in a common plane. By an inspection of Figure 4, it will be understood that the spring plate 71 affords a yieldable support for the sheets between it and the combing wheel 52 and thereby insures a requisite degree of pressure between the combing wheel 56 and the portions 90 of the sheets thereunder. As shown best in Figure 3, a pin 73 which projects laterally from the gear housing lever arm 45, is adapted to slide over the spring arm 31 which is carried by the rock shaft 25. It will be seen therefore that whenever the hooks 22 and 23 have been disengaged by the cam 11 imparting the extreme displacement toward the 95 right to the roller 12 (according to Figure 2), the hook 23 will be lowered with respect to the hook 22 by the combing wheels in lowered position. In order to provide suitable means for raising the combing wheels after 100 the top sheet of the pack has reached a predetermined position, a variable cam 64 carries a pivot pin 74 upon which is mounted a lever comprising an upper arm 75 and a bent lower arm 76. The upper arm 75 of said 105 lever is connected by a rod 77 with a crank arm 78 mounted on a rock shaft 79 within the side frame 10. On the outside of said side frame 10, said rock shaft 79 has keyed thereto another crank arm 80 which is connected by a rod 81 to a crank pin 82 which projects laterally from the cam 11. As shown best in Figure 3, the lower arm 76 of said lever is connected by a link 83 with the forward end of a ratchet bar 84. It will be understood from this description, that the revolution of cam 11 with crank pin 82, is adapted to oscillate the lever 75, 76 on its pivot 74 as long as the rachet bar 84 is free to reciprocate. On the other hand, as soon as 110

115

120

125

130

said rack bar 84 has its movement interrupted, the lower end of lever arm 76 becomes substantially fixed in position with the exception of a slight up and down movement to accommodate the resulting movement imparted to the pin 74. Under this condition, the continued movement of the cam 11 and crank pin 82 produces a clockwise movement of pivot pin 74 about the 5 cam shaft 8 and a similar movement to the trip cam 64. According to the present embodiment of my invention, sheet controlled means for interrupting the ratchet bar 84, is provided in the following mechanism. Oscillatably mounted in the side frames 9 and 10 is a rock shaft 85 which as shown in Figure 5 is provided with a cam arm 86. Journaled on the upper end of cam arm 86 is a cam roller 87 which runs on a cam 88 keyed 10 to the cam shaft 8. A spring 89 is secured at one end to cam arm 86 and has its other end secured to a bracket arm 90 which is keyed to the stay shaft 69. Keyed to the 15 rock shaft 85 on opposite sides of the machine are horizontal arms 91 which carry an oscillatable shaft 92. Mounted on the shaft 92 is a sheet actuated pendulum 93 which normally hangs across the throat 94 formed between the feed tapes 95 and the guides 96 20 which are suspended from the rock shaft 85. As shown best in Figure 3, a pendulum shaft 92 carries a pawl 97 which is adapted to engage the rack bar 84 whenever the pendulum 93 is raised by the forward edge of a sheet as it passes through the throat 94. Drop 25 rollers 98 which are keyed to a drop roller shaft 99 are adapted to engage the sheet as it is fed from the pack. For this purpose, said shaft 99 is journaled in lever arms 100 30 which are keyed to a rock shaft 101 provided with a cam arm 102, a cam roller 103 which is journaled in said cam arm 102 being operated by the drop roller cam 104. For this purpose said cam 104 which comprises relatively 35 adjustable parts for varying the periodic action of said cam to meet the requirements of different size sheets, is keyed to the cam shaft 8. Projecting rearwardly from the center frame bracket 105 is a track bar 40 45 upon which is adjustably mounted a block 107 provided with a depending arm 108 to which is pivotally connected a yoke 109 which serves to mount a tail drag pressure roller 110. A slide 111 which may be 50 55 adjusted to any desired position on the track bar 106, is provided with suitable guides 112 within which reciprocates a ratchet bar 113 which carries at its lower end a tail drag clamping foot 114. Pivotally mounted at 60 65 115 upon the block 111 is an arm 116 which is provided on its outer end with a cam roller 117 which rides on a cam bar 118. Pivoted at 119 on the arm 116 is a pawl 120 which is adapted to engage the rack bar 113 whenever the cam bar 118 is lifting the cam 65 70 75 80 85 90 95 100 105 110 115 120 125 130

roller 117. The forward end of the cam bar 118 is connected to one arm 121 of a lever which is pivoted on a stud 122, the other arm 123 of said lever being connected by a link 124 with the rear arm 125 of a cam lever which is pivoted on a stud 126. The forwardly extending arm 127 of said cam lever is provided with a cam roller 128 which runs on a cam 129 which is keyed to the cam shaft 8. A spring 130 is connected at one end 75 to the cam arm 127 and has its other end connected to the bracket arm 131 on the stay shaft 69. In using the hereinbefore described machine for feeding sheets of small size, it is desirable to have oppositely disposed guide plates 132 as shown in Figure 1 for retaining said sheets in lateral alignment. The forward ends of these guides are held in position by suitable bracket arms 133 which project rearwardly 85 from a stay shaft 134. The operation of my improved machine will now be readily understood and briefly described as follows.

Referring to Figure 4, the parts are shown in their relative positions shortly after the 90 combing rolls have dropped to the pack, by reason of the periodic cam 61 having permitted the combing roll cam arm 58 to drop towards the cam shaft 8. The top sheet has been released by the tail clamp 114 and is 95 progressing under the action of the combing rolls toward the pendulum 93. Supposing that the operation of the machine is normal, according to Figure 7 of the drawings, the sheet has displaced the pendulum upwardly 100 and thrown the pawl 97 into engagement with the rack bar 84. Immediately the lever 75, 76 commences to oscillate about its lower end and thus imparts a clock-wise oscillation to cam 64 (according to Figure 3) 105 which causes the cam roller 63 to rise to the outer run of cam 64, thus throwing the combing rolls to elevated position shown in Figure 3. At the proper instant, the drop rollers 98 drop into engagement with the 110 sheet and drive it forward on to the feed tapes 95. At the same time cam 88 has operated the cam arm 86 to elevate the pendulum 93 and shaft 92 together with the guides 96 to leave an unobstructed passage for the 115 sheet which is being fed from the pack. The parts are then returned to normal and the feeding operation repeated. As the feeding operation goes on, the pack feeding cam arm 13 is operated upon by the protuberance 11' 120 to disengage the hooks 22 and 23. As long as the combing period is not unduly prolonged in bringing the top sheet to the pendulum 93, the combing wheels will always be elevated before the protuberance 11' 125 comes into engagement with the roller 12. In consequence of this normal operation of the machine, the pin 73 which rises with the combing rolls, will have released its pressure on spring arm 31 so that the latch lever 24 130

will be held against the hook 22 and hence will be interlocked therewith as soon as the protuberance 11' has passed the cam roller 12. On the other hand, if as indicated in Figure 2, the combing wheels, during the preceding operation, remained down on the pack while the protuberance 11' was overthrowing the roller 12, the latch arm 24 was depressed during the time that the hooks 22 and 23 were disengaged so that as the roller 12 has passed around the cam 11 after leaving protuberance 11', the hook 22 has moved toward the left to a position in which the hook 23 cannot return into engagement therewith. It will be seen therefore that when the roller 12 reaches the position shown in Figure 2, it will tend to drop into the inner run of the cam 11 in such a way as to impart a feeding rotation to the ratchet 17, tape rollers 18 and feed tapes 19. The position of the pin 29 determines the amount of this feed movement which may be adjusted at will to suit the character of the sheets which are being operated upon. This operation takes place while the combing wheels are elevated. By means of the combing wheels arranged in tandem according to the present invention, it becomes possible to feed sheets of paper less than nine inches dimension in the direction the sheet travels. Heretofore this has been considered impracticable in machines of this character. For example let it be assumed that a sheet six inches in length is to be combed so that its front edge will reach the drop roller 98. The combing wheel cannot be farther than six inches away from the drop roller for the reason that the rear edge of the sheet would be beyond control before the front edge thereof came under the control of said drop roller. Inasmuch as the combing wheel under normal conditions should comb the top sheet about one inch ahead of the next one below in order to prevent the drop roller from dragging along the second sheet with it, it will be seen that a single combing wheel would be operating on only about eight or ten sheets at a time. In order to secure a uniform separation between successive sheets, it has been found necessary to have at least as many sheets again under the combing wheel. This necessity is met in the present invention by the second combing wheel arranged in tandem and in the rear of the same where the number of sheets is greater. In this connection, it has been found desirable to provide some means for cushioning one of the combing wheels to overcome any variation that occurs when the thickness of sheets under the rear combing wheel varies. Thus according to Figure 4, I prefer to employ a strip of spring steel which as shown in Figure 8 is preferably lined with leather on top. I thus secure a double comber action which is capable of

great rapidity, accuracy and uniformity in its action.

While the invention has been illustrated and described with particular reference to the continuous type of feeding machine in which a bank of sheets is automatically advanced over an inclined table, I would have it understood that the main features of the present invention are applicable to pile feeding machines in which a pile is automatically elevated to retain the top sheet in the plane of operation of the separating and feeding-off devices. In the application of the invention to a pile feeding machine, it will be clear that the tandem combing wheels can operate over the inclined delivery board at the front of the pile as shown in Patent No. 1,301,543. With this application of the invention, it will be plain that the elevation of the pile can be automatically controlled by the operation of the combing devices in substantially the same manner as the advance of the pack is controlled in the continuous type of feeder. The expression found in some of the claims referring to the advance of the pack or pile is intended to refer to the supply of sheets operated upon whether in the continuous or pile type of feeder.

I claim:

1. In a sheet feeding machine, sheet combing wheels arranged in tandem and movable together into and out of combing engagement with a pack of sheets, and a table for supporting said pack of sheets, said table being provided with a hollow space corresponding to one of said combing wheels to permit a relative yielding of the pack at that point with respect to the portion of the pack engaged by the other combing wheel.

2. In a sheet feeding machine, the combination with means for supporting sheets to be separated, of sheet combing wheels rotatable about spaced axes, a movable support common to said combing wheels, and means for oscillating said common support for moving said combing wheels into and out of engagement with said sheets.

3. In a sheet feeding machine, the combination with means for supporting sheets to be separated, of sheet combing wheels rotatable about spaced axes, means for moving the rotary axes of said combing wheels about a common axis to move said combing wheels into and out of engagement with said sheets, said sheet supporting means having a yieldable portion disposed beneath one of said combing wheels.

4. In a sheet feeding machine, a table or support for holding sheets to be separated, combing wheels arranged in tandem to rotate in a common plane, a combing wheel support common to said combing wheels and movable towards and away from said table or support, and means for moving said

95.

100

105

110

115

120

125

130

combing wheel support for throwing said combing wheels into and out of engagement with a sheet carried by said table or support for holding sheets.

5. In a sheet feeding machine, a table or support for holding sheets to be separated, a combing wheel support movable towards and away from said table or support, combing wheels journaled in said combing wheel support, and means for moving said combing wheel support for throwing said combing wheels into and out of simultaneous engagement with a sheet carried by said table or support for holding sheets, said table or support being provided with portions yieldable in different amounts for equalizing the pressures of said combing wheels.

6. In a machine of the character described, the combination of sheet supporting means, and a pair of combing wheels movable into and out of engagement with sheets on said supporting means, said sheet supporting means being provided with means for cushioning the pressure of one of said combing wheels.

7. In a machine of the character described, the combination with a table or support for a pile or pack of sheets to be separated, of a pair of combing wheels movable into and out of engagement with said pile or pack, and means for cushioning the pressure of one of said combing wheels.

8. In a machine of the character described, the combination with a table or support for a pack of sheets increasing in thickness from front toward the rear thereof, of combing wheels having a common mount adapting said combing wheels to be moved into and out of engagement with portions of said pack which differ in thickness.

9. In a machine of the character described, the combination with a table or support for a pack of sheets increasing in thickness from front toward the rear thereof, of a combing wheel suitably mounted to move into and out of engagement with a relatively thin portion of said pack, another combing wheel suitably mounted to move into and out of engagement with a relatively thick portion of the pack, means for moving said combing wheels together into and out of engagement with said pack, and means for cushioning one of said combing wheels.

10. In a machine of the character described, the combination with sheet holding means, of sheet combing wheels arranged in a common plane, a rotary shaft to which one of said combing wheels is non-rotatably connected, another shaft to which the other of said combing wheels is non-rotatably connected, gears on said shafts, and an idler interposed between said gears.

11. In a machine of the character de-

scribed, sheet combing means movable into and out of sheet combing position, an oscillatory cam for moving said sheet combing means out of combing position, a lever pivotally mounted on said cam, a reciprocating bar connected to said lever, means for oscillating said lever whereby said bar is reciprocated, and sheet actuated means for interrupting the reciprocatory movement of said bar, said lever oscillating means being adapted thereby to rotate said cam for moving the sheet combing means out of sheet combing position.

12. In a machine of the character described, the combination with a support for a pile of sheets, of a combing wheel support movable in a plane extending longitudinally of the first mentioned support, combing wheels journaled in said combing wheel support and arranged in tandem with respect to the direction of feed, and means for shifting said combing wheel support for moving said combing wheels into and out of simultaneous engagement with a pile of sheets mounted on said pile support, said combing wheels being connected together to rotate in unison.

13. In a machine of the character described, the combination with a support for a pile of sheets, of a combing wheel support movable in a plane extending longitudinally of the first mentioned support, combing wheels journaled in said combing wheel support and arranged in tandem with respect to the direction of feed, means for shifting said combing wheel support for moving said combing wheels into and out of simultaneous engagement with a pile of sheets mounted on said pile support, said combing wheels being connected together to rotate in unison and means for determining the period of activity of said combing wheels, the last said means including a sheet actuated element disposed in the path of a sheet moved by said combing wheels.

14. In a machine of the character described, the combination with sheet holding means, of sheet combing wheels arranged in a common plane, said combing wheels being rotatable about axes spaced apart a distance approximately equal to the diameter of one of said combing wheels, said combing wheels being progressively arranged with respect to said sheet holding means to operate upon an increasing number of sheets.

15. In a machine of the character described, the combination with means for supporting a pack of sheets, means arranged in the path of and actuated by a sheet fed from said pack, combing wheels movable in a common plane into and out of position to feed sheets from said pack towards said sheet actuated means, said combing wheels being arranged in tandem in their plane of movement and progressively arranged with re-

spect to said pack supporting means to operate on a pack which increases in thickness away from said sheet actuated means.

16. In a machine of the character described the combination of a sheet supporting table, with a pair of combing wheels arranged in tandem with respect to the direction of sheet feed and movable into and out of simultaneous engagement with sheets on said table, said table being provided with a hollow or recess beneath one of said combing wheels.

17. In a sheet feeding machine, a pile or pack supporting table, laterally spaced guides on said table, said guides being suitably spaced to hold the sheets of said pile or pack in side registry as they are fed forward in the machine, combing wheels arranged in tandem in the direction of feed and movable in a plane intermediate to said laterally spaced guides, and sheet controlled means for determining the period of comb of said combing wheels, said combing wheels being rotatable about axes spaced from each other a distance approximately equal to the diameter of one of said combing wheels.

18. In a machine of the character described, a power driven shaft, a frame oscillatable on said shaft, a combing wheel shaft journaled in said frame and driven by the first mentioned shaft, a second combing wheel arranged in tandem with the first mentioned combing wheel and driven thereby, a table for supporting sheets to be separated by said combing wheel, and sheet actuated means for controlling the oscillatory movements of said frame.

19. In a machine of the character described, a power driven shaft, a frame oscillatable on said shaft, a combing wheel shaft journaled in said frame and driven by the first mentioned shaft, a second combing wheel arranged in tandem with the first mentioned combing wheel and driven thereby, a table for supporting sheets to be separated by said combing wheel, and sheet actuated means for controlling the oscillatory movements of said frame, said table being provided with a hollow or recess corresponding to one of said combing wheels.

20. In a machine of the character described, a power driven shaft, a frame oscillatable on said shaft, a combing wheel shaft journaled in said frame and driven by the first mentioned shaft, a second combing wheel arranged in tandem with the first mentioned combing wheel and driven thereby, a table for supporting sheets to be separated by said combing wheel, and sheet actuated means for controlling the oscillatory movements of said frame, said table being provided with a hollow or recess corresponding to one of said combing wheels, and a resilient plate for yieldably supporting sheets

under and acted upon by that combing wheel.

21. In a machine of the character described, a combing wheel oscillatable about an axis, a freely journaled cam for lifting said combing wheel from a pile of sheets, a lever movable about an axis on said cam, means for oscillating said lever on said axis and sheet controlled means for constraining said lever to move about a pivotal axis distant from the first mentioned axis, said lever being operably connected to said cam for raising said combing wheel.

22. In a machine of the character described, an automatically controlled sheet combing device, sheet actuated means for determining the duration of the period of activity of said sheet combing device, said means including an oscillatory cam for moving said device out of sheet combing position, a lever pivotally mounted on said cam on an axis eccentric to the oscillatory axis of said cam, a reciprocating bar connected to said lever, means for oscillating said lever on its axis for imparting a reciprocating movement to said bar, and sheet actuated means for interrupting the movement of said bar, said lever being thereby adapted to oscillate said cam for moving said device out of sheet combing position.

23. In a machine of the character described, a sheet feeding instrumentality movable into and out of engagement with a pile of sheets, an oscillatory member adapted when oscillated to remove said instrumentality from the pile, a lever pivotally mounted on said oscillatory member on an axis distant from the oscillatory axis of said member, sheet controlled means including an element adapted to constitute a fulcrum for said lever distant from the pivotal axis of said lever, and means for oscillating said lever, said lever being adapted by said fulcrum to remove said instrumentality from said pile.

24. In a machine of the character described, a combing wheel movable into and out of engagement with a pile of sheets, a freely journaled cam for raising said combing wheel, a lever pivotally mounted on said cam on an axis eccentric to the axis of said cam, means for oscillating said lever, and sheet actuated means for holding said lever to a pivotal movement about an axis distant from its pivotal axis, said lever being adapted to move said cam for imparting a movement to said combing wheel away from said pile.

25. In a machine of the character described, a sheet combing wheel adapted to rise and fall with respect to a pile of sheets, a freely journaled cam for raising said combing wheel from the pile, a lever pivotally mounted on said cam at a distance from the axis of said cam, means for mov-

ing said lever, a ratchet movably connected to said lever, and a sheet actuated pawl adapted to engage said ratchet for imparting a cam oscillating movement to said lever.

26. In a machine of the character described, a sheet combing instrumentality movable into and out of engagement with a pile of sheets, a pivotally supported lever, means for oscillating said lever on its pivotal support, normally movable means trav-

elling in a path removed from the pivotal axis of said lever, said lever being movably connected to said normally movable means, sheet actuated means for interrupting the movement of said normally movable means, and means actuated by said lever when the movement of said normally movable means is interrupted, for removing said sheet combing instrumentality from the pile.

CARL E. CHRISTOPHEL.
